ACTUATING MECHANISM FOR A PLUMBING FIXTURE

Leif Andersen and Edward A. Fredrickson,
Chicago, and Roy H. Zinkil, Oak Park, Ill.

Application October 28, 1938, Serial No. 237,435

6 Claims. (Cl. 4—10)

This invention relates particularly to an actuating mechanism for a swivelable water closet, the latter being adapted for installation and use in a passenger railway car, a ship, or a small apartment where it can be placed within a recess or wall and which, when in use, may be conveniently swung outwardly by manual operation of the actuating mechanism to project into the interior of the room. When not in use the fixture may be swung inwardly, again by manual operation of the actuating mechanism, so as to be concealed within either the interior of the wall or else positioned under suitable furniture and the like, such as a railway car seat, for example. The novel features and detailed description of the swivelable water closet are covered in a copending patent application, Serial No. 214,429, filed June 18, 1938.

The principal object of the invention is to provide a convenient and easily operable actuating mechanism for a swivelable water closet.

Another object is to provide an actuating mechanism for a swivelable water closet which makes possible the movement of the said closet from an inoperative position to an operative position, and conversely from an operative position to an inoperative position without the necessity of touching the said bowl with the hands at any time during the course of its operation.

A further object of the invention is to provide an actuating mechanism for a swivelable water closet which, except for the operating handle or crank, may be concealed from view under or behind walls or fixtures such as furniture or the like.

Other features and advantages of the present invention will hereinafter appear in the following detailed description thereof having reference to the accompanying drawings.

In the drawings:

Fig. 1 is a partly sectional plan view of an embodiment of our invention showing the water closet in the open or operative position.

Fig. 2 is a view similar to that of Fig. 1 but showing the water closet in the closed or inoperative position.

Fig. 3 is a side elevation view showing the water closet in the operative position.

Fig. 4 is a fragmentary sectional view showing the crank and the chain drive adjustment mechanism.

Fig. 5 is a fragmentary partly sectional view showing the chain drive and adjustment mechanism taken at right angles to Fig. 4.

Like reference characters indicate like parts throughout the various views.

Referring to Fig. 1, the closet bowl 1 is shown as having a conventional flushing valve 2 mounted at its side, the latter being supplied with the usual inlet stop valve 3 and the inlet

connection or pipe 4 for attachment to a source of water supply (not shown). The rearward portion of the bowl is provided with an integral flange 5 serving for its purpose as a connection to a suitable discharge elbow fitting 6 which is mounted by means of a rotatable shaft 7 (more clearly shown in Fig. 3) to a pair of supporting brackets 8, the outlet fitting 6 having the usual connection to a trap or septic tank (not shown) while the bracket 8 is connected to a base or floor plate 9 for attachment to a floor or the like. The discharge fitting 6, serving as a support for the bowl by means of its attachment to the flange 5, is provided with a suitable roller 11 (visible only in Fig. 3) arranged to travel upon the base plate 9, as indicated at 12, and having suitable stops 13 and 14 to limit its rotation from the outward position within the room to the inward position within the recess. The foregoing outline sketches the general manner in which the bowl may be mounted for use in connection with the present invention. However, inasmuch as the bowl forms no part of the present invention, a detailed description of the bowl may be dispensed with herein.

As previously explained, the closet bowl 1 is provided with the connecting flange 5 for attachment to the upper end of the elbow fitting 6 and, as more clearly shown in Fig. 3, the attachment is maintained by means of bolting 15 cooperating with the said flange and the said fitting. The discharge fitting 6, which is preferably made of steel or of a similar substantially strong material, is provided with an extending bracket 16 (more clearly shown in Fig. 1) serving as a bearing member for the journaled shaft 7, the latter member having a collar 17 for engagement with an axially aligned bearing member 18 which may be made integral or else may be connected by means of the bolts 19 to the supporting brackets 8, the latter members being fixedly mounted by means of the bolts 21 to the base plate 9. The lower end of the shaft 7 extends within a recess (not shown) in the preferably integral bracket 22 on the discharge fitting 6, the said bracket providing a bearing 23 to which the actuating mechanism may be attached for swivelably moving the closet bowl from an open or operative position to a closed and inoperative position while moving in a horizontal plane.

Attention is again directed to Fig. 1, wherein it will be noted that the base plate 9 is provided with an extension portion 24 upon which is mounted a worm gear speed reducer 25 of conventional type, such as may be found on page 65 177 in catalogue No. 51 of the Boston Gear Works, Inc., Chicago, Illinois. Connected to the speed reducer 25 are the driving shaft 26 and the driven shaft 27. The lever 28 is non-rotatably attached to the driven shaft 27 and has attached 60

to its outer end, by means of a rotatable pin 29, one of the bifurcated ends of the link 31. The other bifurcated end of the link 31 is attached by means of the rotatable pin 32 to the bearing 23 of the bracket 22 on the fitting 6. Thus it can be seen that rotational movement of the driving shaft 26 will produce a rotational movement in the driven shaft 27 which, by means of the lever 28, the link 31, the bracket 22 and the fitting 6, ultimately causes rotational movement of the closet bowl 1 about the axis of the shaft 7.

Referring now to Figs. 4 and 5, conveniently located and preferably mounted upon a wall of the room in which the closet bowl is located, a crank handle 33 and the chain drive 34 are provided by which rotational movement may be transmitted to the driving shaft 26 by manual operation of the said crank, as hereinafter explained. The crank bearing comprises a wall plate 35 having the slotted apertures 36 through which bolts, or screws, or the like may extend for attachment to the wall, the slots 36 being provided to facilitate tensile adjustment of the chain 34 by vertical movement of the plate 35.

As more clearly shown in Fig. 4, the wall plate 35 has the downwardly extending tubular projection 37 and the forwardly positioned crank bearing portion 38. A chain sprocket 39 is non-rotatably attached to the crank journal 41 by means of the pin 42, the said journal extending through the bearing portion 38 and within the wall plate 35 with the sprocket 39 positioned therebetween. Preferably in axial alignment with the drive shaft 26, a lower wall plate 43 is fixedly secured to the wall by means of the bolts, screws or the like extending through the apertures 44. The plate 43 has an upwardly extending tubular projection 45 and the forwardly positioned bearing portion 46. In a manner similar to the crank journal 41, the drive shaft journal 47 extends through the bearing portion 46 and within the wall plate 43 with the sprocket 48 non-rotatably attached to the journal 47 by means of the pin 49, the sprocket 48 being positioned between the plate 43 and the bearing portion 46. The wall plates 35 and 43 are adjustably interconnected by means of the rods 51 and 52 respectively non-rotatably attached to the tubular projections 37 and 45 by the pins 53 and 54, the innermost ends of the said rods being in suitable screw-threaded engagement with the buckle 55, the latter having right-hand threads in one end and left-hand threads in the other end. The journal 47 has an extension 56 to which may be non-rotatably attached the tubular drive shaft connecting member 57.

Again referring to Fig. 1, the drive shaft 26 is preferably provided with a universal joint or flexible coupling 58 which will relieve any transverse stresses which would otherwise be produced in the shaft 26 caused by misalignment of the wall plate 43. The connecting member 57, which may be made from a suitable piece of pipe cut to the proper length to fit the particular installation, is non-rotatably attached to the outermost end of the drive shaft 26 and, as previously mentioned, has its other end non-rotatably attached to the journal extension 56. Thus it can readily be understood that by manual operation of the crank handle 33 rotary motion is transmitted by the chain 34 to the drive shaft 26 and, as previously described, the water closet will be rotated from the position shown in Fig. 1 (open or op-

erative position) to the position shown in Fig. 2 (closed or inoperative), or conversely from the position shown in Fig. 2 to the position shown in Fig. 1, depending upon the direction of rotation of the crank.

It is to be understood that, while a preferred form of the invention has herein been described and illustrated, the invention is not to be limited to the precise construction described above, but includes within its scope whatever changes fairly may come within the spirit of the appended claims.

We claim:

1. An actuating mechanism of the character described in combination with a swivelable plumbing fixture, the said actuating mechanism comprising a chain drive and a geared drive, the said chain drive being manually operable to impart motion through the said geared drive to the said swivelable fixture.

2. An actuating mechanism for a swivelable plumbing fixture comprising, in combination, an angular hollow discharge fitting, a base for the said fitting, the said fitting supporting the said plumbing fixture and being journaled upon the said base, bracket supports for the said fitting, the said actuating mechanism including a chain drive and a geared drive cooperating with the said fitting to produce rotative movement about the vertical axis of the said discharge fitting.

3. A horizontally rotating actuating mechanism for a plumbing fixture comprising, in combination, a plumbing fixture, a journaled fitting therefor, supporting means for the said fitting, a chain and gear drive, lever and linkage means cooperating with the said fitting and the said chain and gear drive, whereby the said fixture is moved from an inoperative to an operative position and conversely, from an operative to an inoperative position upon actuation of the said chain and gear drive.

4. In combination, an actuating mechanism for a swivelable plumbing fixture, an operating handle for the actuating mechanism, combined chain and gear means cooperating with the said handle and the said fixture, whereby upon predetermined movement of the said operating handle the said fixture is movable arcuately in a horizontal plane, the said chain and gear means being suitable for total enclosure adjacent to the said fixture.

5. An actuating mechanism for a swiveling type plumbing fixture having connections respectively to a source of supply and discharge means, a hollow discharge member upon which the said fixture is mounted for swiveling movement, the said actuating mechanism including a crank handle, an adjustably mounted chain drive, a rotatable drive shaft, a geared speed reducer, a lever and a connecting link cooperating with the said discharge member to produce horizontal arcuate movement of the said discharge member upon actuation of the said crank handle.

6. An actuating mechanism in combination with a swivelable closet bowl, the said actuating mechanism comprising a chain drive and a geared drive, the said chain drive being operable to impart arcuate movement through the said geared drive to the said swivelable closet bowl from a concealed position to a position in which the bowl is operatively disclosed.

LEIF ANDERSEN.

EDWARD A. FREDRICKSON.

ROY H. ZINKIL.
